Attorney.

UNITED STATES PATENT OFFICE.

MORGAN A. BALL, OF LOS ANGELES, CALIFORNIA, ASSIGNOR OF ONE-FIFTH TO A. S. DIXON, OF LOS ANGELES, CALIFORNIA.

COTTON PICKER.

Application filed April 15, 1920. Serial No. 373,996.

To all whom it may concern:

Be it known that I, MORGAN A. BALL, a citizen of the United States, residing at Los Angeles, in the county of Los Angeles 5 and State of California, have invented new and useful Improvements in Cotton Pickers, of which the following is a specification.

This invention relates to improvements 10 in cotton pickers such as would be used in a cotton field for engaging cotton in a cotton boll for removing or tearing the cotton fibers therefrom. The invention has for an object the provision of a device of this character which may be carried in the hand and which is compact and will perform the functions required of it in an efficient manner.

In practicing the invention, I provide a casing having an opening at the front 20 and rear ends thereof, and within which casing there is rotatably mounted traveling belts provided with toothed members on the outer periphery thereof and which belts co-act with one another on certain of 25 their surfaces. The belts are likewise exposed through the front opening of the casing so that the toothed members on said belts will engage the cotton in a cotton boll tearing same from the cotton boll and drawing the cotton between the surfaces of the 30 belts and from thence through the opening in the rear of the casing into a receiving means.

The invention further consists in the particular combination, inter-relation, construction, association and relative arrangement of the several parts, elements and features of the cotton picker as illustrated in the drawings described in the specification and finally 40 pointed out in claims.

Other objects and advantages will appear during the course of the following description.

In the drawing:

45 Figure 1 is a vertical side elevation of a cotton picker, certain parts being broken away to show the interior construction of same;

Figure 2 is a fragmentary top plan view 50 of the cotton picker shown in Figure 1, and taken on the line x^2-x^2 , Figure 1, and looking in the direction of the appended arrows;

Figure 3 is a vertical cross sectional view

of the cotton picker shown in Figure 2, and taken on the line x^3-x^3 , Figure 2, and looking in the direction of the appended arrows;

Figure 4 is a fragmentary end elevation of the cotton picker, and looking in the direction of the arrow x^4 shown in Figure 2; and,

Figure 5 is a fragmentary side elevation of a modified form of the cotton picker showing an arrangement for controlling the rotation of the interior working parts of said picker.

Corresponding parts in all the figures are designated by the same reference characters.

Referring to the drawings, A designates a picker casing or housing, B, stripper means contained within said housing, C, mechanism for moving said stripper means, and D means for receiving the picked cotton, all of which elements are used in practicing one embodiment of my invention. 75

The casing A is so constructed that the parts contained therein may be readily accessible for repairs, etc. The casing A includes a member 1 which is U-shaped, and which member 1 has angularly disposed extremities or lugs 2 along the open side thereof. The lugs 2 are threaded as at 3. A cap, cover or plate 4 fits over an open end of the U-shaped portion 1 of the casing A. The cap 4 is likewise provided with ears 5 having perforations 6 therein. The member 4 is held to the member 1 by means of screws 7 passing through the perforations 5 of the member 4 and screwing into the threaded portion 3 of the lugs 2. 80

The particular form of picker shown in Figures 1 to 4 inclusive, has a handle a attached to the casing A, which handle a includes a gripping portion 8 joined to pedestals 9 and 10 which in turn are joined to the casing A as at 11 and 12. The handle a is a medium through which the operator of the picker holds the picker when in use. 95

The casing A is open at its front extremity 13, and at its rear extremity 14, and the member 1 at the front extremity has portions thereof as 15 and 16 converging toward each other. The rear extremity of the casing A as at 17 has a curved portion 18 and a straight portion 19, which straight portion 19 is for accommodating a ring 20 which is provided with angularly disposed ears 21 cooperating with one an-

other and held in close relation to one another by a screw 22 passing through threaded perforations in said ears. When the means D, which may be a sack or a flexible 5 tube or other medium, is attached to the portion 19 of the casing A, the band 20 is passed around such means D and then clamped as just described, so that the means D may be held in a close relation to the 10 casing A and prevented from being detached therefrom.

Within the casing A are rotatably mounted drums b, c, d and e. The drums b and e are placed near the opening of the casing A and at the front extremity thereof, while the drums c and d are placed near the rear extremity of the casing A. The drums b and c are rotatably journaled to the casing A by means of shafts 23 and 24. The shaft 23, fixedly attached to the drum b, is contained in journals 25 and 26 located in the members 1 and 4 respectively. The drum e is likewise fixedly attached to the shaft 24, which shaft is contained within journal 27 in the member 4 and journal 28 in the member 1.

The mechanism for moving the stripper means C ordinarily includes a flexible shaft 29 provided with a bifurcated part 30 co-operating with a corresponding angularly disposed part 31 which latter part 31 is connected to the member 1 and which shaft 29 communicates rotation to the shaft 24. The drums c and d are provided at one end with flanged portions 32 and 33 respectively, and which flanged portions normally engage each other so as to communicate rotation from the driving drum c to the driven drum d.

40 Each of the members 1 and 4 of the casing A is provided with arcuated slots 34. The drum d is provided with a shaft 35 passing through said drum and fixedly attached thereto, and which shaft 35 passes through the slots 34. Arms 36 and 37 are pivotally connected at one end, by means of pins 38 and 39, to the casing A. The opposite ends of the arms 36 and 37 are provided with journaled bushings 40 and 41 and within 45 which journaled portions as at 42 and 43 are passed the opposite ends of the shaft 35. The arms 36 and 37 likewise are provided with depending ears 44 having perforations 45 passing therethrough, and to said ears 44 are detachably joined springs 46 which normally hold the flanged portions 32 and 33 of the drums c and d in relation to each other so that they normally co-act. The drum e is similarly arranged in details to the 50 drum d, that is to say, a shaft 47 passing through said drum e is held in position to the casing A on the exterior portions thereof by means of an arm 48 provided at one end as at 49 with an eye portion 50 and through 55 which eye portion there is passed a pin 51

which in turn joins the casing A on the part designated 4. The opposite end of the arm 48 shown at 52 is provided with a journaled bushing 53 and in this journaled bushing there is passed an end of the shaft 47. The 70 shaft 47 moves within an arcuated slot 54 contained in the member 4 and this arcuation depends upon the length of the arm 48. There is likewise provided on the opposite side an arm 48^a which in all particulars 75 corresponds with the arm 48 just described. There is also within the member 1 a slot corresponding to the slot 54, so that the shaft 47 is evenly held on complementary sides of the casing A. The arm 48 is provided with an ear 55 depending from a portion thereof as at 56, and which ear is perforated as at 57. Resilient means such as a spring 58 is attached at one end of the casing A as at 59, and has its other end passing through the perforation 57, thus at all times causing the drum e to be held in close proximity, but not necessarily touching, its complementary drum b.

The stripper means B includes endless belts 60 and 61, which endless belts are each trained around two of the drums so that the course of each extends substantially parallel with the course of the other. As shown in Figure 1 the belt 60 passes around the drums b and c, while the belt 61 passes around the drums e and d. Each of the belts has on the periphery thereof toothed members 62, laterally arranged thereon.

Referring to Figure 2 it will be observed that the toothed members 62 do not extend completely across the belt, that is, from edge to edge of the belt, or rather, that one end of each of the toothed members as at 63 only extends slightly beyond what would be a median portion of said belt; in other words, the different toothed members are alternately staggered, first one tooth extending from an edge of the belt and partly across same, and then an adjacent tooth extending from the opposite edge of the belt and partly across same, and so on. This particular arrangement of the toothed members on each of the belts 60 and 61 allows the belts to retain their original flexibility so that they will be both laterally and longitudinally flexible, readily adapting themselves to any irregularities such as when cotton is being carried by said belts which will tend to raise a portion of the belt and lower another portion. If the toothed members extended completely across the belt from edge to edge naturally a lateral flexibility of the belt would be impossible. It will also be observed that the toothed member 62 is made so that one of its faces 64 is practically perpendicular with the periphery of the belt member to which it is attached, while another face 65 is angularly disposed to said belt.

Guard means 66 and 67 are arranged to parallel opposite edges of the belt members 60 and 61 so as to prevent any fibrous material that may be carried within the belt 5 from in any way becoming dislodged from the belt and winding itself around the drum shafts, thus tending to clog up the mechanism. It will be observed that the guards 66 and 67 closely encase the peripheries of 10 each of the drum members *b* and *c*, and where the guards 66 and 67 surround the drums *e* and *d* a portion of said guards as at 68 is cut away in order to permit the drums *e* and *d* to move upwardly within 15 the slots 54 and 34 respectively.

Referring to Figure 1 it will now be seen why the casing has its end members 15 and 16 converging downwardly. When the picker casing is engaging a cotton boll at 20 the opening 13 of the casing the downwardly converging parts 15 and 16 extend far enough so that upon rotation of the endless belts the toothed members 62 will engage the cotton in the cotton boll drawing same 25 inwardly and between the adjacent faces 69 and 70 and hence through the casing A and into the receiving means D. Obviously the particular arrangement of each of the drums *e* and *d* permits the belt 61 to move 30 upwardly with relation to the belt 60 and accommodating itself to the varying sizes and quantities of cotton fiber picked. If the cotton fiber or the mass of cotton picked were extremely large the flanged portions 35 32 and 33 of the drums *e* and *d* would move apart and rotation of the belt members 60 and 61 would still continue in relation to each other, for the toothed members 62 would engage alternate tooth members on 40 the belts and tend to keep the belts in the same relation as before. Likewise the particular construction of the toothed members 62 prevents a matting of the cotton fiber.

The modification of the picker shown in 45 Figure 5 includes a handle 71 located on a portion of the picker casing as at 72. The handle 71 is made to resemble a gun handle. In most of the details the picker is similar to the picker shown in Figures 1 to 4 inclusive, the chief variance being in the particular mechanism used for driving the drums *e* and *d* and thence causing the belt members 60 and 61 to travel within the casing A.

In the construction shown in Figure 5 55 the drum *d* is provided with a crown wheel 73 located on one end thereof and the drum *e* is likewise provided with a crown wheel 74. Each of the crown wheels 73 and 74 60 are so located on the drum members that the crown wheels would lie in the same plane. The casing A is provided with journaled bushings 75 and 76 and a shaft 77 is mounted for rotation within said bushings.

65 The shaft 77 is provided with pinions 78

and 78^a meshing with the teeth of the crown wheels 73 and 74 of the drums *d* and *e* respectively.

The handle 71 is recessed as at 79 and within said portion there is disposed a trigger 80 pivotally attached to the inner walls 81 by means of a pin 82. The shaft 77 is extended within the recessed portion 79 of the handle 71. At the lower end of the shaft 77 as at 83 there is provided a cone-shaped member 84 and slightly above said cone-shaped member 84 is a collar 85 splined to said shaft 77. A bifurcated arm 86 is fixedly attached to the trigger 80 and has its bifurcated portions 87 loosely encircling the collar 85 so that a movement of the trigger inwardly will tend to raise the member 84. A flexible shaft 88 passes through a portion of the handle as at 89 and extends to the recessed portion 79 of the handle 71. The end of the flexible shaft 88 as at 90 is provided with a member 91 which member is provided with a concave surface 92 corresponding to a convex surface 93 of the member 84. A spring 94 is disposed between the casing A as at 95 and contacts with a portion of the bifurcated arm 86 as at 96 so that the face 93 of the member 84 and the face 92 of the member 91 are kept in close contact with one another. If the trigger 80 were moved inwardly as just described, the member 84 would tend to be moved upwardly. However, the upward movement of the member 84 will tend to move the faces 93 and 92 from each other; thus when the flexible shaft 88 is rotating the member 91, the drums *e* and *d* will be stationary, until such time as the trigger 80 is released and springs back into place through the action of the spring 94, causing the faces 92 and 93 to again contact with each other. Thus it will be seen that it is possible to allow the belts 60 and 61 to travel at the pleasure of the operator.

The pinion 78 is of a sufficient length so that the teeth of same will mesh with the crown wheel 73 even when the same is moving up or down.

It is obvious that many changes and modifications may be made in practicing the invention as described, all, however, within the scope of the appended claims.

Having thus disclosed my invention, I claim and desire to secure by Letters Patent:

1. A cotton picker comprising a casing having an opening at its front and rear extremities, picker means mounted for travel therein and comprising endless belts provided with coacting toothed members mounted on the periphery thereof, each of said toothed members extending from an edge of a belt to a point beyond the longitudinal middle of the belt, said picker means being partly exposed through the opening in the front of the casing so that the toothed mem-

bers may engage a cotton boll and remove the cotton therefrom, and mechanism for operating said picker means, there being means detachably joined to the casing at the rear opening thereof for receiving the picked cotton.

2. A cotton picker comprising a casing having an opening at its front and rear extremities, rotatable drums journaled to and within said casing, an endless belt passed over said drums, toothed members transversely mounted on the periphery of said belt with each toothed member extending from an edge of the belt to a point beyond the longitudinal middle thereof, said toothed members also being alternately staggered, said endless belt being exposed for a portion through an opening in the front of the casing so that said toothed members may engage the cotton in a cotton boll and remove the cotton therefrom, and mechanism for rotating one of said drums, there being means detachably joined to the casing at the rear opening thereof for receiving the picked cotton.

3. A cotton picker, comprising a casing having an opening at its front and rear extremities, means mounted for travel therein and comprising endless belts provided with prismatic shaped toothed members, triangular in cross section, mounted on the periphery of said endless belts, said endless belts being arranged in substantially parallel opposition and adapted to be presented to a cotton boll to seize and remove the cotton from the boll.

4. A cotton picker, comprising a casing having an opening at its front and rear extremities, rotatable drums journaled to and within said casing, endless belts arranged in substantially parallel opposition and trained each around two of the drums so that the course of each extends substantially parallel with the course of the other, prismatic shaped toothed members, triangular in cross section, transversely mounted on the peripheries of said endless belts, and said endless belts being exposed for a portion in the front of the casing so that the toothed members mounted thereon may engage a cotton boll and remove the cotton therefrom, passing the cotton to the rear of the casing, and mechanism for rotating said drums.

5. A cotton picker comprising a casing having an opening at its front and rear extremities, rotatable drums journaled to and within said casing, endless belts arranged in substantially parallel opposition and trained each around two of the drums so that the course of each extends substantially parallel with the course of the other, prismatic shaped toothed members, triangular in cross section, transversely mounted on the peripheries of said belt, said toothed members being alternately

less belts, and said endless belts being exposed for a portion in the front of the casing so that the toothed members mounted thereon may engage a cotton boll and remove the cotton therefrom, passing the cotton to the rear of the casing, and mechanism for rotating said drums; said casing being slotted at portions adjacent said drums, and spring-actuated means co-acting with said drums for maintaining adjacent faces of the endless belts in close working relation.

6. A cotton picker, comprising a casing having an opening in its front and rear extremities, rotatable drums journaled to and within said casing, endless belts arranged in opposition and trained each around two of the drums so that the course of each extends substantially parallel with the course of the other, toothed members transversely mounted on the peripheries of said endless belts, with each toothed member extending from an edge of an endless belt to a point beyond the longitudinal middle of the belts, said endless belts being exposed for a portion through the opening in the front of the casing so that the toothed members mounted thereon may engage cotton in a cotton boll and remove the cotton therefrom passing the same between said endless belts to the rear of the casing, and mechanism for rotating said drums; there being slots in the casing adjacent said drums, shafts for said drums passed through such slots in the casing, and automatic adjusting means joined to opposite ends of said shafts, whereby the toothed members on the face of one endless belt are caused to be urged toward the face of the opposite endless belt.

7. A cotton picker, comprising a casing having an opening at its front and rear extremities, rotatable drums journaled to and within said casing, an endless belt passed over said drums, prismatic shaped toothed members, triangular in cross section, transversely mounted on the periphery of said belt, said endless belt being exposed for a portion through the opening in the front of the casing so that the toothed members mounted thereon may engage a cotton boll and remove the cotton therefrom, and mechanism for rotating one of said drums; there being guard means longitudinally arranged within said casing and adjacent each side of said endless belt, and extending beyond the periphery of such belt.

8. A cotton picker, comprising a casing having an opening at its front and rear extremities, rotatable drums journaled to and within said casing, an endless belt passed over said drums, prismatic shaped toothed members, triangular in cross section, transversely mounted on the periphery of said belt, said toothed members being alternately

staggered and extending from the edge of the belt to a point beyond the longitudinal middle of such belt, whereby the belt may be slightly flexed both transversely and longitudinally thereof, said endless belt being exposed for a portion through the opening in the front of the casing, so that the toothed members mounted thereon may engage a cotton boll and remove the cotton therefrom, mechanism for rotating one of said drums, and means joined to the casing adjacent the rear opening thereof for receiving the picked cotton.

9. A cotton picker, having in combination: a casing, two endless belt members mounted for travel within said casing, spaced teeth carried on said belt members, said endless belt members being arranged in opposition with the course of one belt substantially parallel with the course of the other belt, and means for maintaining the teeth on the opposed face of one belt member in engagement with the opposed face of the other belt member.

10. A cotton picker having in combination: a casing, two endless belt members mounted for travel within said casing, spaced teeth carried on said belt members, said endless belt members being arranged in opposition with the course of one belt member substantially parallel with the

course of the other belt member, and means for maintaining the teeth on the opposed face of one belt member in resilient engagement with the opposed face of the other belt member; there being means for moving said belt members.

11. A cotton picker, comprising a casing open at its ends, first and second endless belts mounted within said casing with portions thereof adjacent the opening at one end of the casing for picking cotton and conveying the cotton so picked through the casing from end to end thereof, a pair of arms pivoted to the side walls of the casing and carrying a portion of said first endless belt, springs connected to said arms and to the casing for drawing the first endless belt toward the second endless belt, a pair of arms pivoted to the side walls of said casing and carrying a second portion of the first endless belt, and springs connected to said arms and to said casing for drawing a second portion of said first endless belt toward the second endless belt.

In testimony whereof, I have signed my name to this specification in the presence of two subscribing witnesses.
